UNITED STATES PATENT OFFICE

2,620,491

BEDMAKING AID

John Davies Allport, Burlington, Vt.

Application September 12, 1947, Serial No. 773,537

1 Claim. (Cl. 5—131)

1

The present invention relates to bed-making aids and it consists in the combinations, constructions and arrangements of parts herein described and claimed.

It has been the observation of the inventor that beds or bunks, especially those placed against walls, are difficult to make up in that it causes undue stretching, reaching and bending of the body to accomplish the same.

It is accordingly an object of the present invention to provide means whereby a bed or bunk may be tilted and at the same time brought forward to enable the person making the bed to have easy access thereto.

Another object of the invention is the provision of means whereby a bed or bunk may be lowered.

A further object of the invention is the provision of simple and effective apparatus for accomplishing the above objectives.

Other and further objects of the invention will become apparent from a reading of the following specification taken in conjunction with the drawings, in which:

Figure 1 is a plan view of an embodiment of the invention.

Figure 2 is a sectional view taken along line 2—2 of Figure 1.

Figure 3 is a sectional view taken along line 3—3 of Figure 2.

Figure 4 is a fragmentary plan view of a modified form the invention may take.

Figure 5 is a sectional view taken along line 5—5 of Figure 4.

Figure 6 is a fragmentary plan view of a further modification of the invention, and

Figure 7 is a sectional view taken along line 7—7 of Figure 6.

Referring more particularly to the drawings, there is shown therein, in Figures 1 to 3, inclusive, a bed 10 provided with a pair of outwardly extending rollers 11 each centrally mounted adjacent the upper edge of one end of the bed upon an axle 12.

A second pair of rollers 13 is mounted upon axles 14 carried by the bed adjacent the lower rear corner of each end of the bed.

The pairs of rollers 11 and 13 are positioned in upwardly arched trackways 15 formed in blocks 16 attached by means of screws 17 or the like to supports 18.

In the operation of this form of the invention, it will be apparent that, in order to gain better access to the bed 10 for making up the same, it is only necessary to grasp the bed and pull the same forwardly toward the person operating it

2

whereupon the entire bed 10 will move forwardly and the roller 11 will come to rest against the forward end of the trackway 15 and the roller 13 will be elevated to a position adjacent the center of the trackway, thus providing the bed with a forward tilt and enabling the operator to gain easy access to both sides thereof.

In the form of the invention disclosed in Figures 4 and 5, there is shown a bed 10 provided at either end with a forwardly disposed outwardly extending roller 19 mounted upon an axle 20 and a rearwardly disposed roller 21 mounted upon an axle 22.

Supports 23 at either end of the bed have mounted thereon blocks 24 having a horizontally extending trackway 25 formed adjacent the forward end thereof and a forwardly and upwardly extending arcuate trackway 26 formed adjacent the rear thereof. The rollers 19 are mounted in the trackways 25 and the rollers 21 are mounted in the trackways 26.

The operation of this form of the invention is substantially the same as that with respect to the form of the invention shown in Figures 1 to 3, inclusive. The forward rollers, upon the operator pulling the bed forwardly, will move in a straight line while the rollers 21 will be carried upwardly and forwardly, thus giving the desired tilt to the bed 10.

In the form of the invention shown in Figures 6 and 7, there is shown a bed 10 to which is affixed at either end the upper end of a forward link 27 by means of an axle 28 and a rearward link 29 by means of an axle 30. The lower ends of the links 27 and 29 are respectively pivoted to axles 31 and 32 carried by a support 33.

Again, the operation is as above described with respect to the first two forms of the invention. The link 27 being of lesser length than the link 29, when the bed 10 is drawn outwardly, the longer link 29 will cause the rear of the bed to be moved upwardly. The link 29 is bent as indicated at 24 to provide clearance for the same over the link 27 when the bed is drawn outwardly.

It will be understood that the forms of the invention shown herein are merely exemplary and that the identical systems may be utilized for lowering as well as tilting the bed and that counterweights or springs may be provided to allow for the moving of the bed with greater ease. Power, also, may be supplied in the form of hydraulic or other pressure-operated means and the device may also utilize cables and pulleys or balls and sockets to effect the same results.

What is claimed is:

A bed structure adapted to be longitudinally positioned adjacent a wall and comprising a frame having a relatively long inner side, a relatively long outer side, and a pair of end members, a pair of vertical standards each spaced in parallel relation to one of said end members, a horizontally extending block affixed to the inner side of each standard, each of said blocks having an upwardly extending arcuate slot formed therein with its center coincident with the center of said block, a roller carried by each of said end members adjacent the inner side of the frame, and a

roller carried by each of said end members adjacent the center thereof, each of said rollers being positioned in the slot in the block adjacent thereto.

JOHN DAVIES ALLPORT.
